UNITED STATES PATENT OFFICE.

SAMUEL BATTLE LANGHAM, OF NASHVILLE, TENNESSEE.

ADVERTISING DEVICE.

Application filed February 26, 1921. Serial No. 448,031.

To all whom it may concern:

Be it known that I, SAMUEL B. LANGHAM, a citizen of the United States, residing at Nashville, in the county of Davidson and State of Tennessee, have invented certain new and useful Improvements in Advertising Devices, of which the following is a specification.

My said invention relates to an advertising device and it is an object thereof to provide mechanism which shall be operated by clockwork in a regular and positive manner to exhibit a series of pictures or other advertising matter. It is a further object of my invention to provide means for automatically reversing the device to repeat the exhibition of advertising matter in a reverse order and in continuous succession until the clockwork runs down.

Referring to the accompanying drawings which are made a part hereof and on which similar reference characters indicate similar parts,

Figure 1 is a front view of the clockwork in my improved device,

Figure 2, a rear view thereof,

Figure 3, a plan of the entire device showing the clockwork in position,

Figure 4 a section on line 4—4 of Figure 3, and

Figure 5 a sectional view illustrating a modification of my invention.

In the drawings reference character 10 indicates a web adapted to be wound back and forth between two drums 11 and 12 whose heads only appear in the drawings. The shafts or gudgeons of these drums are journaled in bearings on the frame 13. Drum 12 is driven by a sprocket chain 14 passing over sprocket gears on its shaft and on a driving shaft mounted in the casing 15 of the clockwork. A weight 16 is enclosed in a compartment 17, this weight being carried by a cord or cable 18 adapted to be wound on the shaft of drum 12 as the web unwinds therefrom and vice versa. At the other end of the casing is a second weight 19 suspended by a cord 20 and adapted to be wound on the shaft of drum 11 as the web unwinds from the drum and vice versa. These cords with their attached weights serve to keep the web taut as the drums are driven back and forth and in the present embodiment the weight 16 is made heavier than the weight 19 so as to act in effect as a weight motor for winding the web on drum 12 as it is let off from drum

11 the action of the clockwork being thus assisted.

The casing 13 has a door 21 hinged thereto at 22 and frictionally held in closed position by means shown at 23, said door carrying a pane of glass or other transparent material 24 through which the advertising matter on the web 10 may be viewed.

The shaft 25 which drives sprocket chain 14 by a sprocket gear 26 is reversibly driven by means of a pair of beveled pinions 27 and 28 fixed thereon and adapted to engage alternately with a bevel pinion 29 on a shaft 30 carrying at its opposite end a disk 31 with a high part at 32 forming a locking lug for holding the shaft against rotation. A gear 33 indicated in dotted lines is fast on the shaft 30 and a spring motor 34 is geared to shaft 30 by a gear train including gears 35, 36, 37 and 33, the spring motor exerting a constant effort to drive the shaft 30.

The means for reversing the direction of drive and for controlling the action of spring motor 34 will now be described. A second spring motor 38 is connected by a train of gearing comprising gears 39, 40, 41, 42 and 43 (all in dotted lines) to a shaft 44 to drive the same. An escapement comprising a balance wheel 45, a pawl 46, a ratchet 47 and gears 48, 49, 50 and 51, the last mentioned gear meshing with gear 41, controls the action of the spring motor 38 in a conventional manner.

The shaft 44 carries a wheel 52 and this wheel has lugs adapted to strike a lever 53 pivoted at 54 and held in place by spring 55. The movement of the lever due to the action of the spring is adjustably limited by a set-screw 56 at its opposite end. The lever 53 carries a pivoted pawl 57 held by a spring 58 against a ratchet 59 having twelve teeth. This ratchet is fixed to a gear 60, or on the same shaft with the gear. Gear 60 meshes with a gear 61 and is adapted to be held in any one of twelve positions by pawl 62 engaging depressions in the gear. Gear 61 through a pin and slot connection actuates a lever 63 engaging shaft 25 at 64 to move the shaft so as to engage either pinion 27 or 28 with pinion 29 and thus reverse the movement of the shaft.

At the opposite end of shaft 44 from wheel 52 is a disk 65 having a notched periphery. A pair of detents 66 and 67 engage the periphery of the disk and have springs 68 and 69 attached thereto, respectively which force

one end of each detent toward disk 65 so that they will fall quickly into the notches of the wheel when the notches are positioned to receive them. At their rear ends the detents are provided with means to engage the lug 32 of disk 31.

The teeth of disk 65 are so placed that the shaft 30 can be rotated only when gear 29 is fully engaged with one of gears 27 and 28; or conversely, the lugs on wheel 52 bear such relation to the teeth of disk 65 that lever 63 can be moved to reverse shaft 25 only when shaft 30 is held from rotation, by detent 66 or 67.

15 Various modifications of my device will suggest themselves to those skilled in the art, and I do not limit myself to the specific form shown in the drawings, the true scope of the invention being shown by the appended claims.

As an instance of such modification, I may place the clock above the upper roller as shown in Figure 5 at 15'. The chain 14' connects the roller as in the prior modification to the upper roller. A glass window or door 24' is placed at the back of the casing and both sides of the paper can now be used for advertising, both sides being illuminated if the device is to be used at night. Other 30 changes in size, form and relation of parts, etc., will occur to the skilled mechanic within the scope of my invention.

Operation.

35 The relation of parts is such that the wheel 52 will make one revolution per hour and as it carries five lugs it will move the ratchet 59 through parts 53 and 57 once in each twelve minutes. When this occurs the shaft 40 25 will move either to the right or left to reverse its movement and the web which has been wound on one drum will now be unwound from that drum and wound on the other. As the shaft 44 rotates the levers 66 45 and 67 alternately fall into the notches on disk 65. As shown in Figure 2 lever 67 is holding shaft 30 against rotation and when this lever drops into a notch the other lever will be on a high place of the disk 65. Disk 50 31 being released by lever 67, shaft 30 will make one-half revolution when the lug will catch on the projection of lever 66, the movement of shaft 30 and parts driven thereby giving web 10 a quick movement of sufficient 55 length to change the sign and then holding it stationary until the lever 66 is lowered to release lug 32, by which time lever 67 is in engaging position. Preferably I provide disk 65 with sixty teeth so that the wheel 31 60 will be released at intervals of one-half minute but the number of teeth may be varied according to the length of the film to be exhibited or in accordance with the length of time it is desired that an individual advertisement or other display shall be shown.

When the shaft 44 has made one-fifth of a revolution; that is, when the device has run about twelve minutes in one direction it will be reversed and run for twelve minutes in the opposite direction as heretofore explained. To prevent any retrograde movement or back lash of the shaft 44 whereby the sequence of operations might be disturbed I provide a multiple pawl arrangement 70 near disk 65 having a plurality of 75 pawls of varying length, one of which will always be in position to engage a tooth of wheel 65.

Having thus fully described my said invention, what I claim as new and desire to 80 secure by Letters Patent, is:

1. In a changeable exhibitor, a plurality of drums and means for winding a web back and forth from one to the other comprising a shaft, a spring motor for driving the same, means for reversing the movement of said shaft, means for driving the shaft intermittently and a second spring motor connected to operate the reversing means, substantially 85 as set forth.

2. In a changeable exhibitor, a plurality of drums and means for winding a web back and forth from one to the other comprising a driving shaft, a second shaft geared to drive the first shaft reversibly in opposite 95 directions, a constantly acting motor to drive the second shaft and means to interrupt the movement of the second shaft including a pair of detents adapted to hold the shaft from rotation and means for alternately disengaging said detents, substantially as set forth.

3. In a changeable exhibitor, a plurality of drums and means for winding a web back and forth from one to the other comprising 100 a driving shaft, a second shaft arranged to drive the first shaft reversibly in opposite directions, a constantly acting motor to drive the second shaft and means to interrupt the movement of the second shaft including a 105 pair of detents engageable alternately with the shaft and means driven by a constantly acting motor for alternately disengaging said detents, substantially as set forth.

4. In a changeable exhibitor, a pair of drums and a web adapted to be wound back and forth from one to the other and means for maintaining the web in taut position comprising a pair of weights, a cord attached to each weight and also attached to 110 the shaft of a drum to be wound thereon as the web is unwound, substantially as set forth.

5. In a changeable exhibitor, a drum and means for winding a web thereon comprising a shaft, a spring motor for driving the shaft, a disk on the shaft having a lug and a pair of oppositely located detents adapted to engage said lug in alternation, and automatic means to release said detents after a 115 120 125 130

predetermined interval of time, substantially as set forth.

6. In a changeable exhibitor, a drum and means for winding a web thereon comprising a shaft, a spring motor for driving the shaft, a disk on the shaft having a lug and a pair of oppositely located detents adapted to engage said lug in alternation, automatic means to release said detents after a predetermined interval of time, a notched wheel acting on said detents to release them alternately from said disk and motor operated means for driving said wheel, substantially as set forth.

15 7. In a changeable exhibitor, a drum and means for driving the same comprising a shaft, a pair of detents, means on the shaft adapted for alternate engagement by the detents and means for successively releasing said detents at the expiration of predetermined times of equal length, substantially as set forth.

25 8. In a changeable exhibitor, a drum and means for driving the drum comprising a shaft, a pair of detents and means on the shaft adapted for alternate engagement by said detents, a disk having projections to engage and release said detents, means to drive said disk in one direction and means to prevent retrograde movement thereof, substantially as set forth.

35 9. In a changeable exhibitor, a pair of drums, a web adapted to move from one to the other and means for driving the same comprising a shaft having a pair of pinions, a second shaft having a pinion adapted to mesh alternately with the first pair, means for driving the second shaft to engage said pinions alternately with the pinion of the second, said means acting only when the second shaft is locked against rotation, and means for locking the second shaft against rotation at intervals, said reversing means acting only

45 when the second shaft is locked against rotation, substantially as set forth.

10. In a changeable exhibitor, a drum, a driving shaft carrying a pinion, a pair of pinions in driving connection with the drum and mounted for alternate engagement with the first named pinion, a lever for moving the pinions alternately into engagement with

the first, a gear having pin and slot engagement with the lever, a second gear meshing with the first, means for driving the same intermittently and means for locking the reversible pinions in engaging position, substantially as set forth.

11. In a changeable exhibitor, a driving shaft carrying a pinion, a pair of pinions connected to the drum and mounted for alternate engagement with the first named pinion, a lever for moving the pinions alternately into engagement with the first, a gear having pin and slot engagement with the lever, a second gear meshing with the first, means for driving the same intermittently and means for locking the reversible pinions in engaging position comprising depressions in the second gear and a yieldable detent for engaging said depressions, substantially as set forth.

12. In a changeable exhibitor, a drum and means for driving the same to wind a web thereon comprising a driving shaft and reversing mechanism therefor including a ratchet, a pawl engageable therewith, a disk having lugs thereon to actuate the pawl and motor operated means to drive the disk, a connection between said ratchet and said driving shaft whereby rotation of the disk causes said driven means to rotate the driving shaft, substantially as set forth.

13. In a changeable exhibitor a casing having opposed transparent sides, a drum in the top portion of the casing, another drum in the bottom portion of the casing, a web extending between them and adapted to be wound from one drum to the other whereby both sides of the web are exposed to the transparent sides at the same time, and means mounted in the casing at one end thereof for and reversibly automatically driving one of the drums, and means on the other drum constantly tending to rewind the web thereon, substantially as set forth.

In witness whereof, I have hereunto set my hand and seal at Nashville, Tennessee, this seventeenth day of February, A. D. nineteen hundred and twenty-one.

SAMUEL BATTLE LANGHAM. [L. s.]
